UNITED STATES PATENT OFFICE

HARRY A. GOYKE AND ROY C. LA DUE, OF CLINTON CORNERS, NEW YORK; NAOMI GOYKE ADMINISTRATRIX OF SAID HARRY A. GOYKE, DECEASED

ROAD-MAP HOLDER

Application filed March 6, 1929. Serial No. 344,739.

The present invention relates to an improved road map holder more particularly adapted for use with automobiles.

When making automobile tours, frequent recourse to road maps is usually necessary in order to discover whether or not the correct route is being followed. Road maps as now obtainable are inconvenient to handle, easily torn, and often misplaced when most needed.

One object of the invention, therefore, is to provide a holder for carrying road maps and the like in such a manner that easy reference may be had thereto.

Another object of the invention is to provide a map holder having means permitting ready removal and substitution of the maps carried therein.

A further object of the invention is to provide a map holder having maps attached to spring actuated rollers capable of drawing the maps up into the container after the necessary information has been secured therefrom.

A still further object of the invention is to provide a map holder which may be manufactured cheaply and which will tend to retain the maps carried therein in an unsmeared condition.

These and other objects will be seen more clearly as the description of the invention proceeds.

In the drawings:

Figure 1 is a front elevation, the front plate of the device being removed and showing one of the rollers partly broken away and in section.

Figure 2 is a cross sectional view of the device on the line 2—2 of Figure 1, and showing the device mounted above the windshield of an automobile.

Figure 3 is a transverse sectional view on the line 3—3 of Figure 1, looking in the direction indicated by the arrows.

Referring more particularly to the drawings, the numeral 1 indicates a casing, substantially U-shaped in cross section, and having top and bottom walls 2 and 3, end walls 4 and 5, and a back wall 6. The top and bottom walls 2 and 3 are bent inwardly at their outer margins to form channel shaped flanges

7. Associated with the casing 1 is a front plate or closure 8 having channel shaped flanges 9 mating with the flanges 7 for slidably connecting the front plate with the casing.

55

As shown in Figure 2, the device is preferably secured above the windshield of a motor vehicle by screws 10 extending through the front wall 6 of the casing, a portion of a motor vehicle being conventionally illustrated. It is to be understood, however, that different types of mounting means may be used with the device, depending upon specific requirements of installation.

60

The bottom wall 3 of the casing is provided with a longitudinally extending rectangular opening and soldered or otherwise secured at their ends to the casing, at the ends of said opening, are longitudinally disposed strips

65

11. These strips are preferably formed of metal and the longitudinal margins thereof are bent back to overlie the strips and provide smooth edges. As best shown in Figure 2, the strips define a plurality of slots 12. Embracing the margin of the bottom wall of the casing at the front of the foremost slot is a strip 13 soldered or otherwise secured to the casing, said strip providing a smooth surface at the forward edge of said slot.

75

Mounted on the end walls 4 and 5, but in spaced parallel relation thereto, are diagonally disposed supporting strips 14 and 15 which are soldered or otherwise secured to the end walls. Formed in the strip 14 is a series of spaced slots 16 and formed in the strip 15 is a series of openings 17 each of said openings aligning with its opposite slot.

85

Removably mounted in the casing are rollers 18. Extending through the rollers are rods 19 having flattened end portions 20 to selectively engage in the slots 16 while the opposite ends of said rods are selectively engageable in the openings 17. Although we have shown provision for three rollers, a greater or less number may be employed, as desired.

90

Surrounding the rods 19 are coil springs 21 having corresponding ends attached to the rods and their opposite corresponding ends attached to the rollers.

100

Wound on the rollers 18 are maps 22, although some other form of indicia may be used. The inner end portions of said maps are glued or otherwise secured to the rollers 5 while the marginal outer end portions of the maps extend through the slots 12 and are folded and stitched to provide hems 23. Slidably mounted in the hems 23 are rods 24 formed of wood, metal, or other suitable material. The rods 24 engage the casing to maintain the outer ends of the maps 22 in such a position that they may be readily grasped and brought into use.

As will now be seen, the free end of any 15 one of the maps may be grasped and the map pulled down into view, and since the strips 11 and 13 provide smooth surfaces at the forward edges of the slots 12, abrasion of the maps will be effectually avoided. When not 20 in use, the maps are, of course, wound upon the rollers to be housed and protected by the casing while, when desired, the rollers with the maps thereon may, after removing the front plate 8, be readily removed at the front 25 of the casing.

Having thus described the invention, what is claimed is:

1. A device of the character described including a casing open at the front thereof 30 and having top and bottom walls provided with flanges at the open front of the casing, the bottom wall being formed with a slot, a roller operatively mounted in the casing and removable through the open front of said 35 casing, a flexible element normally wound on the roller and extending at its free end through said slot whereby said element may be withdrawn to extend exteriorly of the casing in view, and a front plate normally closing the front of the casing and having flanges 40 mating with the flanges of the casing and slidably connecting said front plate with the casing.

2. A device of the character described including a casing open at the front thereof and having top and bottom walls provided with flanges at the open front of the casing, a roller operatively mounted in the casing and removable through the open front of 50 said casing, a flexible element normally wound on the roller and extending at its free end through the bottom wall whereby said element may be withdrawn to extend exteriorly of the casing in view, and a front 55 plate normally closing the front of the casing and having flanges mating with the flanges of the casing and slidably connecting said front plate with the casing.

In testimony whereof we affix our signatures.

HARRY A. GOYKE. [L. S.]
ROY C. LA DUE. [L. S.]
